COMBINED DISPLAY CARD AND ARTICLE HOLDER

Henry M. Unger, 565 Solingen Walter-Dodde-Strasse 16,
(or P.O. Box 100102), Solingen, Germany

Filed Jan. 15, 1975, Ser. No. 541,238

Claims priority, application Germany Sept. 24, 1974

Term of patent 14 years

Int. Cl. D9—03

U.S. Cl. D9—191

FIG. 1

FIG. 2

FIG. 3

FIG. 1 is a top edge view of a combined display card and article holder embodying my new design;

FIG. 2 is a front elevational view;

FIG. 3 is a bottom edge view;

FIG. 4 is a side elevational view;

FIG. 5 is a side elevational view opposite to that of FIG. 4; and

FIG. 6 is a rear elevational view.

I claim:

The ornamental design for a combined display card and article holder, as shown.
